UNITED STATES PATENT OFFICE.

JOHN O. OLSON, OF RED WING, MINNESOTA.

INCUBATOR.

1,119,630.

Specification of Letters Patent.

Patented Dec. 1, 1914.

Original application filed March 27, 1912, Serial No. 686,607. Divided and this application filed November 25, 1913. Serial No. 803,026.

To all whom it may concern:

Be it known that I, JOHN O. OLSON, a citizen of the United States, residing at Red Wing, in the county of Goodhue and State 5 of Minnesota, have invented a new and useful Incubator, of which the following is a specification.

The device forming the subject matter of this application is a structure which has 10 been divided out of my co-pending application, Serial No. 686,607, filed March 27, 1912, which has since become Patent No. 1,100,146, dated June 16, 1914, and purporting to set forth sundry improvements in an incubator.

15 The objects of the present invention are to provide an incubator in which the pipe which conducts the heated air into the incubator, is terminally connected with a vent pipe entering the incubator, the construction being such that when the heated air is 20 finally discharged into the vent pipe, a draft will be created in the vent pipe, thereby facilitating the ventilation of the incubator.

A further object of the invention is to 25 provide novel means for connecting the air supply pipe with the hot air delivery pipe, so that the moistened air, traversing the air pipe will be heated, prior to entering the incubator.

30 A further object of the invention is to provide a construction in which the heated air, having traversed the delivery pipe, will be re-heated to some degree, before entering the vent pipe, thereby facilitating the draft 35 in the vent pipe.

With the foregoing and other objects in view, which will appear as the description proceeds, the invention resides in the combination and arrangement of parts and in the 40 details of construction hereinafter described and claimed, it being understood that changes in the precise embodiment of the invention herein disclosed can be made within the scope of what is claimed without departing from the spirit of the invention.

In the accompanying drawings:—Figure 1 shows the invention in vertical longitudinal section, parts appearing in elevation; Fig. 2 is a top plan, the lid of the outer case 50 being removed; Fig. 3 is a sectional detail of the moistening mechanism and attending parts; and Fig. 4 is a fragmental vertical section showing the means whereby the sections of the pipes are assembled with the cases.

In carrying out the invention there is provided an inner case 1, having outlets 2, securing a ventilation of the case. The case 1 is surrounded by an outer case 51. To one end 10 of the outer case 51 is secured a hood 60 3, within which is supported a water cup 4, in any desired manner. In the present instance, the water cup 4 is upheld by an angle bracket 5, adjustably secured to the end wall 10 of the case 51 by means of a clamp and 65 slot connection 6, permitting a lowering of the bracket 5, so that the cup 4 may be inserted into and be removed from the hood 3. The upper end of the hood 3 is partially closed, and is entered by an air supply pipe 70 7, provided with a damper 8. A tubular sleeve 9 is inserted through the end walls of the cases 1 and 51, the outer end of the sleeve 9 being closed as shown at 11. The air supply pipe 7 enters one side of the 75 sleeve 9.

Supported by a bracket 12 is a lamp 14, the chimney of which enters a heating drum, denoted generally by the numeral 15. The heating drum 15 includes an inner wall 80 16 and an outer wall 17, connected by a bottom 18 in which there are air inlet openings 19. The upper end of the outer wall 17 is connected with the cylindrical portion 20 of the drum, the same having a top 21; provided with a draft outlet opening 22.

A hot air delivery pipe 23 enters one side of the cylindrical portion 20 of the drum, and passes inwardly through the end wall 11 of the sleeve 9, the end wall 11 preventing 85 an indraft of air between the delivery pipe and the sleeve. The delivery pipe 23 extends along the longitudinal center of the case 1, substantially the full length of the case, the pipe 23 diverging, as shown at 24, 90 to form a pair of return bends 25. The return bends 25 terminate in connections 26 which enter the delivery pipe 23, adjacent its initial end, as indicated at 27. Across the interior of the portions 26 of the return 95 bends, imperforate partitions 28 extend, the partitions being located between the delivery pipe 23 and the extremities 30 and 32 of the return bends 25. Thus there are formed in the portions 26 of the return 100 bends, heating chambers 29 which communicate with the delivery pipe 23 adjacent its initial end.

The portions 30 and 32 of the return bends enter an upright tapered pipe 110

31, the wider end of which is upwardly disposed, the narrower, lower end of the vent pipe entering the case 51 and communicating with the space between the cases 51 and 1 as shown at 33.

5 Located within the case 1 is a thermostat 34, operatively connected with a lever 35, fulcrumed intermediate its ends in the end wall of the inner case and extending 10 through the end wall of the outer case. The outer end of the lever 35 is operatively united with a connection 36, connected at its upper end to the lever 37, supported upon a bracket 38, the free end of the lever 15 37 supporting a damper 40, positioned above the opening 22 in the top of the drum 15.

In practical operation, the lamp 14 will 20 heat the drum 15 and cause the air to be drawn inwardly and upwardly through the openings 19 in the bottom of the drum, the air being heated by contact with the outer face of the inner wall 16. From the drum 15, the heated air will enter the delivery pipe 23, and traverse the return bends 25 25 thereof, the heated air passing into the extremities 30 and 32 of the return bends, and thus entering the vent pipe 31. The heated air entering the vent pipe 31 will traverse the same, causing a draft in the vent pipe, and creating a suction through the portion 33 of the vent pipe, whereby the foul air 30 between the cases 1 and 51 will be withdrawn, the outlets 2 furnishing further communication with the interior of the case 1.

35 As the air traverses the delivery pipe 23, the temperature within the chambers 29 will be raised, causing a heating of the partitions 28, and causing a heating of the air which lies between the partitions and the portions 40 30 and 32 of the return bends. Therefore, the air as it passes from the return bends 25, into the portions 30 and 32 of the return bends, will be heated to some extent, before it enters the vent pipe 31. Since the air is 45 thus heated, prior to entering the vent pipe 31, the draft through the vent pipe will be increased accordingly.

When the air within the case 1 is drawn 50 outwardly through the openings 2 and beneath the case 1 through the vent pipe 31, in the manner hereinbefore described, fresh air will be drawn upwardly through the hood 3, about the water cup 4, the entering air being thus moistened. The air entering the hood 3 will traverse the pipe supply 17, controlled by the damper 8, and enter the sleeve 9, the outer end of which is closed. As the air enters the sleeve 9 it will come 55 into contact with the initial end of the delivery pipe 23 and be heated, a supply of moist, fresh, heated air thus passing into the casing 1, through the open inner end of the sleeve 9.

60 The function of the thermostat 34 and the 65 parts controlled thereby is common and

well understood and needs no specific explanation.

Having thus described the invention, what is claimed is:—

1. In an incubator, a case; a delivery pipe 70 entering the case and having a return bend discharging outside of the case, the return bend having a branch entering the delivery pipe adjacent the initial end of the delivery pipe; and a partition extended across the 75 branch between the delivery pipe and the outlet end of the return bend; and means for heating the initial end of the delivery pipe.

2. In an incubator, a case; an upright 80 vent pipe entering the case at its lower end; a delivery pipe entering the case and having a return bend entering the vent pipe to create a draft in the vent pipe, thereby to facilitate the ventilation of the case; the return bend having a branch entering the delivery pipe; a partition in the branch, between the delivery pipe and the outlet end of the bend; means for heating the initial end of the delivery pipe; and means for 85 supplying air to the case.

3. In an incubator, a case; an upright vent pipe entering the case; a delivery pipe entering the case and having a return bend entering the vent pipe to create a draft in 90 the vent pipe, thereby to facilitate the ventilation of the case; means for heating the initial end of the delivery pipe; the return bend having a branch entering the delivery pipe; and a partition in the branch, between 95 the delivery pipe and that portion of the bend which enters the vent pipe.

4. In an incubator, a case; a delivery pipe 100 entering the case and having a return bend discharging outside of the case, the return bend having a branch entering the delivery pipe; and a partition in the branch, between the delivery pipe and the discharge end of the bend.

5. In an incubator, a case; a delivery pipe 110 entering the case and having a return bend discharging outside of the case; means for heating the initial end of the delivery pipe; the return bend having a branch entering the delivery pipe adjacent the heating 115 means; a partition in the branch between the delivery pipe and the outlet end of the return bend, the partition being located adjacent the heating means, the partition dividing the branch into two chambers, one of which communicates with the delivery pipe and the other of which communicates with the return bend adjacent the outlet end of the return bend, to effect a heating and an acceleration of the air, as the same approaches the outlet end of the return bend.

6. In an incubator, a case; an air supply pipe entering the case; a moistening device movable with respect to the mouth of the pipe to regulate the moistening of the air in 130

the pipe; a damper operating in the pipe and controlling the passage of air through the pipe irrespective of the amount of moisture in the air; and a heating means for the pipe, the point of application of the heating means with respect to the pipe being spaced remotely from the moistening device.

In testimony that I claim the foregoing as my own, I have hereto affixed my signature in the presence of two witnesses.

JOHN O. OLSON.
